FUEL OIL BURNER

Filed Oct. 22, 1928

Fig. 1

INVENTOR,

BY *Caleb J. May,*
David S. Bain,
ATTORNEY.

UNITED STATES PATENT OFFICE

CALEB J. MAY, OF BELLINGHAM, WASHINGTON, ASSIGNOR OF ONE-FOURTH EACH TO
CHARLES B. MAY, IVAN D. MAY, AND JAMES W. HUTTON, ALL OF BELLINGHAM,
WASHINGTON

FUEL-OIL BURNER

Application filed October 22, 1928. Serial No. 313,996.

My invention relates to improvements in fuel oil burners, more especially intended for kitchen ranges and house furnaces, and has for an object to provide a burner suited to 5 use fuel oil in which there are no moving parts and combustion proceeds on downwardly inclined surface of small declivity.

Another object of my improvement is to provide for said combustion under the action 10 of distributed down-draft air.

Another object of my improvement is to provide for said combustion on surfaces in superposed relation each successive surface adapted to receive the unconsumed fuel from 15 the surface next above.

Another object of my improvement is to provide against the spreading of liquid fuel over surfaces where its presence would be undesirable.

20 Further objects of my improvements will appear as the description proceeds.

I attain these and other objects of my improvement with the device illustrated in the accompanying sheet of drawings which form 25 a part of this application and in which Figure 1 is a plan view of my burner, Fig. 2 is a side elevation of the burner in place in the fire pot of a kitchen range in section on a longitudinal medial plane and Fig. 3 is a 30 plan view of one of the combustion rings.

Similar characters indicate similar parts throughout.

Certain parts are broken away to show others hidden thereby.

35 With more particular reference to the designated parts: A frame 4 has side walls and a rear end wall on which bears cover 5 preferably rabbeted to engage frame walls 4 from which it is removable. Walls 4 together with cover 5 constitute a bottomless box with one open end.

Cover 5 has central hole 6 therethrough to the margin of which is fastened conical spider 7 preferably having three legs inclined diagonally upward and meeting in central hub 47.

Spider arms or legs 7 have spaced horizontal steps 8, 9 and 10, and risers a_8 , a_9 and a_{10} .

50 Annular margin 11 around the upper end of hole 6 is on a lower level than the top sur-

face of cover 5 and is surrounded by annular groove 12. Annular margin 14 around the lower end of hole 6 is reduced to the dimensions of a lip by annular groove 13 around the same.

55

Combustion ring 15 is adapted to bear on lower step 8 of spider legs 7 with riser a_8 extended therethrough. Combustion ring 16 is smaller than ring 15 and bears on step 9 with riser a_9 extended therethrough. Combustion ring 17 is smaller than ring 16 and is placed to bear on step 10 with riser a_{10} extended therethrough.

60

The peripheries of rings 15, 16 and 17 are preferably in the surface of a cone parallel with spider arms 7. The upper surface of each of rings 15, 16 and 17 is preferably that of a flat truncated cone, and the lower surfaces thereof, a_{15} , a_{16} and a_{17} are preferably concave as shown to cause oil flowing 65 from combustion ring to combustion ring to leave the same at the periphery thereof.

70

Conical nozzle 18 has threaded central hub 19 to engage in a tapped central hole in the upper end of spider hub a_7 . The under side 75 of the base of nozzle 18 is preferably concave around hub 19 to cause oil flowing over the nozzle to leave the same at the periphery of its base. Axial hole 20 extends entirely through nozzle 18 and registers with hole b_7 . Central boss b_{18} projects from the vertex of 80 the nozzle and hole 20 is continued therethrough and its outer end is tapped to engage screw 22 which stops said hole at its upper end. Holes 21, three of which are 85 shown in Fig. 2, are preferably four in number and are spaced around the junction of the nozzle and boss b_{18} . These holes provide outlets from hole 20 to the conical surface of nozzle 18.

90

The lower end of hole b_7 is tapped to engage the end of feed pipe 23 which connects with a pressure source of fuel oil not shown.

95

Needle valve housing 24 is included in pipe 23 and has needle valve 25 mounted therein. Valve stem 26 connects valve 25 with handle 27 located at a conveniently accessible place.

Drip pan 28 is preferably integral with the side walls of box 4 and has a hopper-shaped bottom from the lowest part of which 100

leads overflow pipe 29 leading to a suitable receptacle not shown. Pan 28 is vertically beneath hole 6 and will catch any oil dripping from lip 14 around said hole.

5 As shown in Fig. 2, combustion rings 15, 16 and 17 are separated in the vertical by spaces 30 therebetween. Also nozzle 18 is similarly separated by a space 30 from top ring 17.

10 In Fig. 2 the burner is shown in place in kitchen range 31 bearing on grate 32 of the fire box thereof. Preferably bricks 33 are used to occupy the grate space around burner box 4.

15 In operation: Needle valve 25 is opened by turning handle 27 thereof. Fuel oil flows from nozzle outlets 21 on to the surface of the nozzle where it is ignited. The oil not consumed on said nozzle flows downward on 20 to ring 17 to which the combustion is communicated. Oil not burned on ring 17 flows down on to ring 16 where said combustion is communicated, and such oil as is not consumed on ring 16 passes on to ring 15 where, 25 it is assumed, the residue of all that is flowing through outlets 21 will be consumed. However, any surplus not consumed on the lowest combustion ring will dip down into groove 12 at which place the combustion will 30 continue to consume it. And, if such a quantity of oil is flowing from said nozzle outlets that groove 12 becomes filled with oil, then it flows over margin 11 down over the walls of hole 6 from which it drips into pan 28 to pass 35 out therefrom through pipe 29 into a receptacle as above stated.

The burner is operating at full capacity when oil is burning on the surface of bottom ring 15, and only an excessive opening of 40 valve 25 will provide a surplus to flow into drip pan 28.

Heat from the oil burning on the rings will cause a movement of air through the openings of grate 32 into box 4 and thence through 45 hole 6 and upward through spaces 30 between said rings and between the lower ring and cover 5 and also between the top ring and nozzle 18. The movement of this air current will be quite strong and as it impinges 50 on concave surfaces $a15$, $a16$, $a17$ and $a18$ it will be deflected and provide a down draft of considerable force on top of the sheets of flame on said rings and on the cover, if oil is provided for groove 12. These rings be- 55 come very hot and the sheets of oil thereon are thin allowing very complete oxidization of the oil and gases generated therefrom and causing intense heat of combustion.

Having thus disclosed my invention, what 60 I claim as new therein and desire to secure by Letters Patent is,—

An oil burner consisting of a base, a three-legged spider mounted on said base projecting upward therefrom having spaced sets of 65 steps on the outer surfaces of said legs, a

frusto conical annular disc mounted on each of said sets of steps, a liquid fuel nozzle mounted centrally above the topmost of said discs having outlets to deliver liquid fuel on the upper surface of said topmost disc, a pipe 70 connected to said nozzle outlets, and a controllable valve in said pipe.

CALEB J. MAY.
